UNITED STATES PATENT OFFICE.

THOMAS W. PRIOR AND FREDERICK A. CHURCH, OF VENICE, CALIFORNIA.

MERRY-GO-ROUND.

1,082,764.

Specification of Letters Patent. Patented Dec. 30, 1913.

Application filed March 11, 1912. Serial No. 683,126.

To all whom it may concern:

Be it known that we, THOMAS W. PRIOR and FREDERICK A. CHURCH, both citizens of the United States, residing at Venice, in the 5 county of Los Angeles and State of California, have invented a new and useful Merry-Go-Round, of which the following is a specification.

Our present invention relates to merry-go-rounds so constructed that a racing feature 10 is embodied therein.

The invention more particularly relates to a merry-go-round having a revolving table or platform divided into a plurality of segments or sections, each segment or section 15 of which is provided with a group of rider supports, such as horses, so that the riders on the merry-go-round ride in groups, each segment of the table containing its own device for producing the racing feature for 20 the group of horses on that particular segment, so that the outcome of the race in each group on the table is in doubt both to the contestant riders and to the operator 25 of the merry-go-round until the finish signal is displayed.

One of the main objects of our invention is to produce a merry-go-round of the character described having a revolving table and 30 a plurality of groups of rider supports, the rider supports of each group being adapted to change their relative positions during the revolution of the table.

Another object of our invention is to produce a merry-go-round of the character described of simple form and construction which may be operated with great simplicity.

Other objects and advantages will appear 40 hereinafter from the following specification.

Referring to the drawings, which are for 45 illustrative purposes only:—Figure 1 is a plan view of a merry-go-round showing the embodiment of a form of our invention. Fig. 2 is a vertical, sectional view of the device shown in Fig. 1, showing the horses on one segment only. Fig. 3 is a plan view, 50 partly in section, of a portion of the table of the merry-go-round. Fig. 4 is a longitudinal, sectional view of a portion of the merry-go-round. Fig. 5 is an enlarged, vertical, sectional view of the switch mechanism and electrical connections for one set of drums. Fig. 6 is a side elevation of the 55 switch mechanism shown in Fig. 5. Fig. 7 is a sectional, plan view of the tracks for sup-

porting the rider supports on the table and operating means therefor. Fig. 8 is a side elevation, partly in section, of a portion of the driving means.

Our invention consists of a revolving table 1 provided on the underside with a series of inner and outer wheels 2 and 3 adapted to support the table on inner and outer circular tracks 4 and 5, respectively. Any 60 desired means for revolving the table upon the tracks may be employed. In the present instance we have shown a table provided with a groove 6 formed in the outer edge thereof adapted to receive a cable 7 which passes around a driving pulley 8 mounted on a driving shaft 9, the cable 7 being kept under proper tension by means of an idle pulley 10 mounted on a tension spring 11 secured at 12 to any stationary 65 object.

Upon the common forms of merry-go-rounds the rider supports, which consist in different instances of forms of birds and animals, are either fixed to the table or are 70 so mounted on the table that a movement is given to the rider supports imitating the action of the animal which the rider support represents, but we have devised means whereby the rider supports may be arranged 75 in groups on the table, the rider supports in each group being adapted to change their relative longitudinal position. This is accomplished in the following manner: The table 1 is provided with a plurality of 80 groups of slots 15, 16, 17, 18, 19 and 20, the slots 21, 22, 23 and 24 in each group being arranged concentric to each other within a segment of the table. Each slot is provided with a pair of channel bars 26 85 arranged longitudinally therein to form track means for a carriage 27 having supporting wheels 28 which engage the channel bars 26. Each carriage 27 has pivotally mounted thereon, by means of a pin 30, 90 a supporting arm 31, the upper end of which is pivotally mounted at 32 to the body of the rider support, which, in the present instance, is shown as a horse 40, the lower end of the arm 31 being provided with a pin 33 eccentrically mounted in a supporting wheel or roller 34, which roller 34 is adapted to travel on the floor 35 below the table. The roller 34 being eccentrically 95 mounted on the end of the arm 31 imparts a longitudinal swinging movement to the horse caused by the lower end of the arm 100 105 110

31 rising and falling as the roller 34 travels upon the floor 35. The natural movement of the horse in running is more closely imitated by pivotally connecting a link 36 at 37 to the horse, the other end of the link 36 being connected by means of a pin 38 to the arm 31 below the pin 30 on the carriage 27, thereby producing a compound movement or action of the horse.

10 Means are provided for causing the horses 40 to move forwardly in their respective slots which consist of a cable 41, one end of which is secured to an eye 42 on the carriage 27, the other end of which is secured to a drum 43 mounted on a shaft 44 carried by any suitable supporting means on the underside of the table 1. Each shaft 44 is provided with a drum for each carriage, and a shaft 44 is provided for each 15 group of slots on the table 1. The drums 43 are loosely mounted on shafts 44 and are adapted in the present instance to be rotated by the shafts 44 by means of a magnetic clutch 45 keyed to the shaft 44 by 20 means of a key 46, it being understood that any of the well known forms of magnetic clutches may be used for this purpose, the magnetic clutch herein shown being indicated diagrammatically. Each shaft 44 is 25 driven by means of a sprocket wheel 45 mounted thereon, which sprocket wheel 45 is driven by means of a sprocket chain 39 driven from a sprocket wheel 47 mounted on the shaft 48 of one of the adjacent supporting wheels 3 of the table. Each carriage 27 is provided with an arm 50 which extends outwardly therefrom a sufficient 30 distance to engage projections or lugs 51 and 52 formed on the opposite ends of a bar 53 slidably mounted in suitable brackets 54 secured to the underside of the table 1. The bar 53 is provided with a contact pin 55 adapted to enter between the blades 56 of a switch 57 for the purpose of closing an 35 electric circuit hereinafter described for the purpose of operating the magnetic clutches on the shaft 44.

The table 1 is provided with a series of arms 60 extending inwardly therefrom for 40 the purpose of supporting a circular frame or support 61. Mounted on the support 61 is a plurality of bars 62, one for each group of rider supports on the table. To each bar 62 is secured a stationary arm 63 and a movable arm 64 hinged thereto at 64'. Pivoted to the arm 63 is the link 65 of a toggle 66, the other link 67 of the toggle being pivoted at 68 to the movable arm 64. Secured to the link 65 of the toggle 66 in any suitable 45 manner is a make and break brush or blade 70 adapted to engage a circular contact ring 71, of copper or other suitable material, when the toggle is in the full line position shown in Fig. 6. The pin 72, by means 50 of which the lower link 65 is pivotally

mounted on the arm 63, is fixed with relation to the link 65 and is provided with a pair of arms 73 and 74 extending in opposite directions therefrom for the purpose of breaking the toggle to either side of the 55 center line, the toggle being held in broken position by means of a coil spring 75, one end of which is secured to the arm 64 and the other end of which is secured to the arm 63. The arms 73 and 74 are operated by 60 means of spring blades 76 and 77, each having its inner end pivotally connected at 78 and 79 respectively to the opposite ends of a lever 80 pivotally mounted at 81 in a bracket 82 secured in any suitable manner to a stationary support 83. Handle 84 is secured to the lever 80 for the purpose of rocking the same on the pivot 81 so as to bring the blades 76 and 77 into engagement with the respective arms 73 and 74 on the pin 72. A stop 85 is mounted on the arm 63 to limit the movement of the links of the toggle in the opposite direction, that is, in the dotted line position 85 shown in Fig. 6.

90 Fixed to the arm 63 by means of blocks 86 of insulating material is a spring contact brush 90 adapted to ride on a circular ring 91, of copper or other suitable material, mounted on the support 83. The rings 95 71 and 91 are connected respectively to the opposite sides of an electric current supply 100 by means of wires 101 and 102. The brush 70 is electrically connected through the toggle 66 and movable arm 64 by means 100 of a wire 105 with the switch 57 of each magnetic clutch 45. Each bar 53 is connected by means of a wire 106 with its associated magnetic clutch 45. Each magnetic clutch 45 is connected by means of a wire 107 to a wire 108 connected to the brush 90.

105 It is understood that each group of rider supports and its associated drums and magnetic clutches are controlled by an electric 110 circuit as just described and that each group of rider supports is independent of the other groups of rider supports. The only portion of the electric circuit common to all 115 the groups consists of the motor 100 and wires 101 and 102 which connect the motor to the rings 71 and 91 respectively.

120 The operation is as follows:—The table is revolved in the direction shown in Fig. 1 through the medium of cable 7 and the driving pulley 8. The horses 40 in the position shown in Fig. 1 are in the position which they occupy at any time during the ride. Before the ride has started and when the riders are mounting their respective horses, the horses in each group are at the rear end 110 of their respective slots in the table. The operator then starts the table revolving by any of the well known forms of mechanical controlling means; at the same time mov- 125 130

ing the operating arm 84 which is on the starting and finish line of the ride to throw the spring blade 77 into the path of the arm 74, so that when the arm 74 of the toggle 5 switch mechanism controlling each group of rider supports reaches the spring blade 77 the arms 74 of the respective toggle or main switch mechanism are moved into the full line position shown in Fig. 6, thereby bringing the contact blade 70 thereof into engagement with the ring 71 which closes an electric circuit through ring 71, wire 101 to the motor or source of electric energy 100, thence through wire 102 to ring 91, thence through blade 90, wire 108 and wire 107 to the respective magnetic clutches 45, thence through wire 106 to bar 53, the bar 53 being in the position shown in Fig. 7. Electric current passes through contact pin 55, switch 57, wire 105, thence through movable arm 64, toggle 66, make and break blade 70 to the ring 71, thereby completing the circuit. The electric circuit when closed, as just described, draws 20 the magnetic clutch into engagement with the drum 43, and as the table revolves forwardly in the direction indicated by arrow in Fig. 1 the drums 43 on the respective shafts 44 are rotated by means of the respective magnetic clutches 45 to slowly wind the 25 respective cables 41 on the respective drums 43, thereby slowly pulling the carriages 27 and the respective horses thereon forwardly in the channel bars 26 in the respective slots 30 in the table. As the slot 21 of each group is shorter than all of the other slots in the group, the carriages 27 in the slots 21 reach the forward end of the slot prior to the time that the carriages in the slots 22, 23 and 24 35 reach the respective forward ends of the slots. When the carriage 27 in any slot reaches the forward end thereof, the contact 50 on the carriage strikes the lug 52 on the bar 53 and moves the same forwardly into 40 the dotted line position shown in Fig. 7, thereby moving the contact pin 55 out of engagement with the blades 56 of the switch 57, thereby breaking the electric circuit heretofore described. The carriage then being 45 carried forward with the table by the friction of the rollers 28 in the channel bars 26 in the table, is retarded by the friction of the roller 34 on the floor 35, which causes the carriage 27 and the horse 40 carried thereon to lag or drop behind the movement of the table, which lagging behind of the horse 40 continues until the carriage 27 reaches the rear end of the slot in the table; at the same time unwinding the cable 41 50 from the drum 43 on the shaft 44. When the carriage 27 reaches the rear end of the slot the contact 50 carried by the carriage comes in contact with the lug 51 on the rear end of the bar 53 and moves the bar 53 back 55 into its original position with the contact 55 thereon between the blades 56 of the switch 57, thereby again closing the electric circuit heretofore described through the magnetic clutch 45 which engages the drum 43, thereby rotating the same with the shaft 44 which causes the carriage 27 to again be drawn forwardly in the slots in the table until the carriage reaches the forward end of the slot and the circuit is again broken, as above described. The forward and backward movement of the carriages in their respective slots in the table is repeated a number of times during the ride, and as the respective slots in each group of slots in the table are of different lengths, the position of the horses in the respective groups of slots on the table is in doubt until the make and break brush 70 is moved out of engagement with the contact ring 71. This is done by moving the operating arm 84 to bring the blade 76 into engagement with the arms 73 of the respective toggle switch mechanism as they pass the finish line to break the toggle into the dotted line position shown in Fig. 6, thereby moving the brush or blade 70 70 into the dotted line position shown in Fig. 6, which breaks the electric circuit with the motor so that the magnetic clutch for each drum on the table moves out of engagement with its respective drum and all of the horses through the medium of the frictional contact of the rollers 34 with the floor 35 lag 75 behind the movement of the table until each horse has reached the rear end of the slot at the time the table has stopped its revolution due to the momentum of the table after the power has been shut off therefrom. The end of the race takes place at the time the operator breaks the circuit by moving the brush 70 out of engagement with the contact ring 71, this being indicated to the rider by a signal connected by means of a link 115 with the operating arm 84 and a signal box 116 on a standard 117 on the support 83. The signal marks the finish line, being at the 80 point where the operating arm 84 is placed, and as each group of horses passes thereby the leading horse of each group wins the race for that particular group. Any form of signal may be used for this purpose, in the present instance the words "Start" and "Finish" being shown, the word "Start" being uncovered when the race starts, and the word "Finish" being uncovered, by operating the link 115, when the operator 85 moves the arm 84 to break the circuit through the brush 70 and the ring 71. While we have shown and described the particular form of mechanism for causing the horses to assume different relative positions during the revolving movement of the table of the merry-go-round, it is understood that we do not limit our invention to the particular form of operating devices herein shown and described, but our invention 90

covers a revolving table having groups of rider supports thereon and means for causing change in the relative position of the rider supports in each group.

5 The blades 76 and 77 heretofore described are constructed of spring metal of sufficient strength to throw the operating arms of the toggle switch, but are so arranged that after throwing the arms the blades assume their 10 original position in the path of the falling operating arms of the respective switches.

What we claim is:—

15 1. A merry-go-round comprising a single table, means for revolving the table, a plurality of groups of rider supports on said table, means for limiting the relative rotative movement of each group with the table, and means for changing the relative rotative position of the rider supports in each 20 group on said table during the revolution of the table.

25 2. A merry-go-round comprising a table, means for revolving said table, a plurality of groups of rider supports on said table, and means for causing each of said rider supports to travel faster than said table to change the relative position of the rider supports in each group during the revolution of the table.

30 3. A merry-go-round comprising a table, means for revolving said table, a plurality of groups of rider supports on said table, and means for causing each of said rider supports to travel alternately faster and 35 slower than said table to change the relative position of the rider supports in each group during the revolution of the table.

40 4. A merry-go-round comprising a table, means for revolving said table, a plurality of groups of rider supports on said table, each rider support consisting of a carriage longitudinally movable with respect to said table, a seat mounted on said carriage, means for moving each of said carriages during 45 the revolution of said table, and means for limiting the movement of said carriages to change the position of the carriages in each group during the revolution of the table.

50 5. A merry-go-round comprising a table having a plurality of groups of slots therein, means for revolving said table, a rider support mounted in each slot, means for independently and automatically moving 55 each of said rider supports in its respective slot during the revolution of the table to change the relative position of the rider supports in each group during the revolution of the table.

60 6. A merry-go-round comprising a table having a plurality of groups of slots therein, the slots in each group being of different lengths, means for revolving said table, a rider support mounted in each slot in said 65 table, means for independently moving each

of said rider supports in its respective slot during the revolution of the table to change the relative position of the rider supports in each group during the revolution of the table.

70 7. A merry-go-round comprising a table having a plurality of groups of slots therein, the slots in each group being of different lengths, means for revolving said table, a rider support mounted in each slot in said table, means for independently moving each of said rider supports in its respective slot alternately faster and slower than the table to vary the relative position of the rider supports in each group during the revolution of the table.

75 8. A merry-go-round comprising a floor, a table supported above said floor having a plurality of groups of slots therein, means for revolving said table, a rider support mounted in each slot, releasable means for independently moving each of said rider supports faster than the table, and means on each rider support adapted to engage the floor to cause its associated rider support to move slower than the table when said releasable means is in inoperative position.

80 9. A merry-go-round comprising a floor, a table above said floor having a plurality of groups of slots therein, the slots in each group being of different lengths, means for revolving said table, a rider support mounted in each slot, propelling means mounted on said table for independently moving each rider support forward in its respective slot, means for releasing said propelling means, and means carried on each rider support adapted to engage said floor to cause each of said rider supports to move rearwardly when said propelling means is in inoperative position.

95 10. A merry-go-round comprising a floor, circular rails secured to said floor, a table having a plurality of groups of slots therein, the slots of each group being of different lengths, a series of supporting wheels mounted on said table adapted to engage said rails, means for revolving said table, a rider support mounted in each slot in said table, a shaft mounted on said table at the forward end of each group of slots, a plurality of drums loosely mounted on each shaft, a cable connecting each rider support to one of said drums, a plurality of clutch means on each shaft adapted to independently drive each drum from the shaft, means operated by each rider support to operate its respective clutch to drive its respective drum from said shaft to cause the rider support to move forwardly in its respective slot, means operated by each rider support to release its respective clutch means, and means on each rider support adapted to cause the rider support to move rearwardly in its slot when said clutch is released.

11. A merry-go-round comprising a floor, a pair of circular rails secured to said floor, a table having a plurality of groups of slots therein, the slots of each group being of different lengths, a series of supporting wheels mounted on said table adapted to engage said rails, means for revolving said table, a carriage mounted in each slot, a seat on each carriage, an arm extending downwardly from said carriage, a roller on said arm adapted to engage the floor, a shaft mounted on said table at the forward end of each group of slots, a plurality of drums loosely mounted on each shaft, a cable connecting each carriage to one of said drums, independent clutch means on each shaft for each drum thereon adapted to drive the respective drums from their respective shafts, means on each carriage for placing its respective clutch in operative and inoperative position, means for consecutively placing the clutches on each shaft in operative or inoperative position, and means for driving each shaft.
12. A merry-go-round comprising a floor, circular rails secured to said floor, a table having a plurality of groups of slots therein, the slots of each group being of different lengths, a series of supporting wheels mounted on said table adapted to engage said rails, means for revolving said table, a carriage mounted in each slot, a seat above each carriage, an arm having its upper end pivotally connected to said seat, means for pivotally connecting an intermediate portion of said arm to said carriage, a roller eccentrically mounted on the lower end of said arm adapted to engage the floor, a link pivotally connected to said seat at its upper end and pivotally connected at its lower end to said arm below said carriage, a shaft mounted on said table at the forward end of each group of slots, a plurality of drums loosely mounted on each shaft, a cable connecting each carriage to one of said drums, independent clutch means on each shaft for each drum thereon adapted to drive the respective drums from their respective shafts, means whereby each carriage places its respective clutch means in operative position when said carriage is at the rear end of the slot, means whereby each carriage places its respective clutch means in inoperative position when the carriage is at the forward end of the slot, means for placing all the clutches on each shaft in operative or inoperative position, and means for driving each shaft from the supporting wheels of said table.
13. A merry-go-round comprising a floor, circular rails secured to said floor, a table having a plurality of longitudinal slots therein, each of said slots being of different length, a series of supporting wheels mounted on said table adapted to engage said rails, means for revolving said table, a rider support in each slot, a shaft mounted on said table at the forward end of said slots, a plurality of drums loosely mounted on said shaft, a cable connecting each of said rider supports with one of said drums, independent clutch means on said shaft for each drum, an electric circuit, means in said electric circuit operated by the respective rider supports to place the respective clutches in operative position when the rider support is at the rear end of its respective slot and to place the clutch in inoperative position when the rider support is at the forward end of the slot, means for opening and closing said circuit to simultaneously place all of said clutch means in operative or inoperative position, and means on each of said rider supports adapted to engage the floor and cause the rider support to move from the front to the rear of the slot when the associated clutch means is in inoperative position.
14. A merry-go-round comprising a single revoluble table, means for revolving the table, a group of rider supports on said table, means for changing the relative rotative position of the rider supports in said group during the revolution of said table, and means for limiting the relative rotative movement between said rider supports and said table.

In testimony whereof, we have hereunto set our hands at Venice, California, this 4th day of March, 1912.

THOMAS W. PRIOR.
FREDERICK A. CHURCH.
